US0D1055956S

(12) **United States Design Patent** (10) **Patent No.:** **US D1,055,956 S**
(45) **Date of Patent:** ** *Dec. 31, 2024

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jae Woo Chang**, Cupertino, CA (US); **Patrick Lee Coffman**, San Francisco, CA (US); **Nathan de Vries**, San Francisco, CA (US); **Christopher P. Foss**, San Francisco, CA (US); **Robert Garcia, III**, San Francisco, CA (US); **Heena Ko**, San Francisco, CA (US); **Stephen O. Lemay**, Palo Alto, CA (US); **Marcel van Os**, Santa Cruz, CA (US)

(73) Assignee: **Apple Inc.**, Cupertino, CA (US)

(*) Notice: This patent is subject to a terminal disclaimer.

(**) Term: **15 Years**

(21) Appl. No.: **29/907,636**

(22) Filed: **Jan. 8, 2024**

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
